UNITED STATES PATENT OFFICE.

JAMES DAWSON, OF HARRISBURG, PENNSYLVANIA, ASSIGNOR OF ONE-HALF TO JOHN H. DAWSON, OF SAME PLACE.

ROLLER-MILL.

SPECIFICATION forming part of Letters Patent No. 399,186, dated March 5, 1889.

Application filed May 3, 1888. Serial No. 272,738. (No model.)

To all whom it may concern:

Be it known that I, JAMES DAWSON, a citizen of the United States, residing at Harrisburg, in the county of Dauphin and State of Pennsylvania, have invented a new and useful Roller-Mill, of which the following is a specification.

My invention relates to mills for grinding corn or other feed perfectly fine at one operation, in which three reductions are effected before the stock is passed through the mill, principally by a fixed main roll and three movable lesser rolls supported in swiveled bearings, so as to yieldingly work against the periphery of the main roll, and passing the stock from roll to roll in a circuit about half-way around the main roll.

I carry out the objects of my invention by means illustrated in the accompanying drawings, in which—

Figure 1 is an end elevation of my mill with driver-pulley and parts of cog-gears omitted; Fig. 2, a like view of the opposite or right end of the same mill; Fig. 3, a top view of my mill; Fig. 4, a vertical cross-section of the same, made by a vertical plane on the indicated line $H^0 H^1$ of Fig. 3; Fig. 5, a vertical section through the axis of the eccentric lever, it and other parts being shown in perspective looking toward the broken-away casing; Fig. 6, a plan of the eccentric-lever studs or sleeves; Fig. 7, a plan view of the stud-attaching bolt; Fig. 8, a longitudinal section of said stud or sleeve; Fig. 9, a longitudinal section of the eccentric-lever bar; Fig. 10, a bottom view of one of the corresponding three-way joints; Fig. 11, a longitudinal division of one of the swivel-bearing levers and part of the wall of the machine-frame to which it is fulcrumed.

Similar reference-letters denote similar parts in the several views.

In the vertical parallel cast-iron walls A and B, which are framed together by braces Q' and bolts B', is centrally journaled, upon fixed horizontal bearings, the large or main roll R³. On an arc of about a semicircle, upon swiveled bearings, are journaled near the main roll a series of lesser rolls, R⁴ R⁵ R⁶. The bearings of these rolls are mounted on levers S, fulcrumed to the walls A and B. The

free ends of these several levers are pivoted to rods p q r, respectively, which hold the lesser rolls to the main roll alike at both their ends. The three draw-rods on each side converge and cross in three-way joints, which latter, with the rods yieldingly carried therein, are themselves supported on an eccentric lever, by which they and the lesser rolls are adjusted, as will be further explained. As each of the series of lesser rolls, in conjunction with the main roll, reduces the stock finer, three reductions are effected in one passage of the stock through the mill, suitable chute-boards, 5 6 7, being provided to direct the stock to the successive points of reduction, and exit-boards S⁴, to finally discharge the material, forming a hopper beneath the rolls. All these boards are supported on the hopper-frame X, extended interiorly down between the walls A and B and the rolls, as shown in Fig. 3. The main shaft O has upon one end the pulley G and cog-wheel C', which intergears with the wheels C on the shafts k and m, as shown in Fig. 2. Upon the other end of shaft O is another pulley G and a second cog-wheel C', which intermeshes with wheel C on shaft l, as shown in Fig. 1. By this arrangement the oppositely-intergeared shafts, k, l, and m, and the rolls mounted thereon are rotated in an opposite direction to the main roll. The duplication of the pulley G is to balance the shaft and to reduce the wear at its fixed bearings. When the small rolls are moved out of grinding contact, the said cog-wheels C C' still maintain their intermeshed relation, their teeth being long enough to permit sufficient adjustment to intermit the grinding without throwing said wheels out of gear.

The outer-roll bearings X' are on the levers S, which latter are fulcrumed or pivoted at their inner ends to the frames A or B by eccentric studs or wrists D², each provided with the nut-form head D and adjustably secured in place by the screw-bolt D'. By turning said head when the said bolt is slackened the eccentric stud may be adjusted to bring the peripheries of the outer rolls in tram with the main roll, according to the wear of the peripheries. The free ends of said levers are clevis form, having pivoted thereto by pins

² the tenons d , into the outer ends of which are screwed the draw rods or bars $p q r$, respectively, which rods are suitably secured by the jam-nut O' . The swivel-bearings X' project through holes in the walls $A B$, and come flush with their inner surfaces. The said draw rods converge and cross each other in the three-way joints $Y Y' Y^2$, which are three-way cored to admit said rods freely there-through, and are at their bases formed with abutments, into which are fitted the wrists of the eccentric shifting-lever E' , swiveled there-to by a set-screw, J , working in a groove, E^3 , at each end of said lever E' , which latter is journaled in extensions Q of the frames $A B$, as shown in Fig. 5. The said draw rods or bars $p q r$ are extensively threaded at their rear portions, and have thereon the jam-nuts $J' J^2$, for limiting the throw of said rods by stopping against the inner ends of the several branches of the three-way joint. The exterior end of each branch of the joint is shouldered, and retains thereon the one end of a coiled spring, V , into whose outer end sets the shouldered end of a hand-nut, R , screwed upon the outer end of each of said rods, for adjusting the tension of the said springs and movable bearings as desired. The combination of the said swiveled bearings, draw-rods, three-way joints, regulating jam-nuts, and springs, with the hand-nuts V , and eccentric shifting-lever E' , provided with the handle E , constitute a multiple radial jack, whereby the three smaller rolls are brought up to engage the main roll for work, or are withdrawn from the same by the downward movement of the all-controlling handle E of the lever E' when the grinding is to be stopped. In either alternative the said handle E may be clamped in place by the binding hand-bolt f^2 engaging the nut f^3 through the circularly-slotted standard f , also mounted on the adjacent portion of the frame A concentrically with the axis of the lever E' .

45 The swiveled bearings of the rolls have the cap-plates bolted thereto at b reversibly, that the oil-pockets formed thereon may be right side up for containing the lubricant, whether the said bearings are pivoted at their lower or at their upper ends, as shown in Figs. 1 and 3.

50 In the hopper-receptacle X is mounted the feed device, consisting of the bar f , transversely and horizontally supported in bearing-plates N , attached to the exterior of the hopper-walls. Journaled on said bar is the shoe P^3 , provided with the extension or handle P^4 , arranged to have contact by the action of gravity with the under side of the projections of a tappet-wheel, W^2 , which is rotated upon its supporting-shaft W' , which latter is journaled in the plates S on the hopper-walls. Said shaft W' has thereon the pulley P^4 , and it is driven from a pulley on the shaft k by the belt W . Said shoe is rocked upon the axle f and delivers the corn or other feed over its end, as indicated by the arrow. Portions of the hopper-bottom 3 4 and converged portions (not

shown) deposit the feed upon said shoe P^3 , and a slide, W^4 , provided with the knob W^3 , may be slid down upon the shoe and shut off the feed entirely when required for change of stock.

The rolls may be smooth or corrugated. They are preferably cut spirally and finer in the order as follows: main roll R^3 coarse, 75 rolls $R^4 R^5$ finer, and the finishing - roll R^6 finest, so that one course of stock through the mill produces finished stock or needs no further reduction.

I claim—

1. In a roller-mill, the combination of the main roll journaled in fixed bearings in the center of the frame, three smaller adjustable rolls rotating in the opposite direction to the main roll, levers provided with bearings supporting said lesser rolls, eccentric studs mounted on the frame and each supporting one end of said levers, three-way union-joints, each provided with an abutment, rods connecting said joints with one end of each of the said levers, respectively, said rods being screw-threaded at their ends and each provided with a spiral spring and a hand-nut, and an eccentric bar journaled in bearings in the frame, and having its ends swiveled in the abutments of the three-way joints, substantially as described.

2. In a roller-mill, the combination of the main roll journaled centrally in the frame in fixed bearing, and having upon its shaft the opposite similar pulleys, G , and gear-wheels C' , three smaller rolls having bearings on levers S , supporting said bearings, said rolls having their shafts provided with gear-wheels C , intergeared constantly with said gear-wheels 105 on main-roll shaft, eccentric studs D^2 , adjustably bolted on the machine-frame and supporting said levers as pivots at their inner ends, three-way joints $Y Y' Y^2$, provided with abutments M , rods $p q r$, pivoted to the levers, 110 respectively, on the inner ends, and passing through the three-way union-joints at their outer ends, so as to bring the lesser rolls into grinding contact with the main roll, the spiral springs V and hand-nuts R , one on each of 115 said rods, and the eccentric bar E' , journaled in fixed bearings on the frame, and swiveled at its ends in the abutments M on both said three-way joints, substantially as and for the purposes described.

3. In a roller-mill, the combination of the main roll fixedly journaled centrally in the frame, and having on both ends of its shaft a driving-pulley, G , and a gear-wheel, C' , three smaller rolls having bearings on movable levers supporting said bearings, said rolls having their extended shafts provided oppositely with gear-wheels C , intergeared with the corresponding gear-wheels on the main-roll shaft, the eccentric studs D^2 , supporting one end of 125 said levers, respectively, and adapted to be adjusted to compensate for wear of the rolls, the three-way joints $Y Y' Y^2$, having abutments M , rods $p q r$, pivoted to the movable

levers S, respectively, at their inner ends, and passing through the tubular branches of the three-way union-joints at their outer ends, said rods being provided with jam-nuts J' 5 J² to limit their outward movement, spiral springs V and hand-nuts R, one on each of the ends of said rods exterior to said joints, and the eccentric bar E', swiveled at its ends to the abutments M on the three-way joints, and provided with the operating-handle E and 10 means for holding it in its adjusted position, substantially as described.

JAMES DAWSON.
